UNITED STATES PATENT OFFICE

161,422

COMBINED PURSE, IDENTIFICATION CASE, AND WALLET

Herbert S. Chase, New York, N. Y.

Application April 14, 1950, Serial No. 9,200

Term of patent 14 years

(Cl. D87—3)

To all whom it may concern:

Be it known that I, Herbert S. Chase, a citizen of the United States of America, residing in New York city, county of New York, and State of New York, have invented a new, original, and ornamental Design for a Combined Purse, Identification Case, and Wallet, of which the following is a specification, reference being had to the accompanying drawing, forming part thereof, wherein:

Figure 1 is a front elevational view of a combined purse, identification case and wallet showing my new design in closed position.

Figure 2 is a side elevational view.

Figure 3 is a rear elevational view.

Figure 4 is an open plan view thereof disclosing the identification case and utility pocket members in detail, and

Figure 5 is a perspective view of Figure 4, disclosing the purse and wallet members in detail.

I claim:

The ornamental design for a combined purse, identification case, and wallet, substantially as shown and described.

HERBERT S. CHASE.
